CARBURETOR

Frank C. Mock, East Orange, N. J., assignor to
Bendix Stromberg Carburetor Company, South
Bend, Ind., a corporation of Illinois

Application August 30, 1930. Serial No. 478,847

12 Claims. (Cl. 261—34)

This invention pertains to carburetors for mobile internal combustion engines and more particularly has reference to acceleration pumps for supplying additional fuel whenever the throttle is quickly opened.

This invention is an improvement in the type of acceleration pump disclosed in the copending application of Don Cole, Ser. No. 189,983, filed May 9, 1927, of common ownership with this application.

While the acceleration pumps disclosed in the copending application referred to work satisfactorily under ordinary conditions when the temperature under the hood does not exceed 100° F., difficulty is experienced in summer weather when the hood temperature ranges from 100° F. to 130° F. or higher. Under these conditions, with present automobile fuels which contain fractions forming vapor bubbles between 100° 20 F. and 130° F., considerable amounts of vapor accumulate in the piston chamber or dome. If the acceleration pump is operated while the chamber is partially filled with this vapor, as soon as the outlet communication is opened the 25 vapor escapes in one sudden rush driving all the fuel in the passages before it and giving so rich a mixture that the engine misses and stumbles. Another disadvantage of the previous type pumps mentioned is that at slightly 30 warmer temperatures, they evacuate entirely and give no accelerating charge whatever.

An object of this invention is to overcome the above difficulties by providing an acceleration pump whose fuel outlet is below the point of 35 egress of fluid past the piston so that no vapor is ejected into the fuel passages during the operation of the pump.

Another object of my invention is to provide an improved acceleration pump in which even 40 though the liquid fuel content thereof is half boiled away no vapor is ejected into the mixing chamber of the carburetor during the operation of the pump.

Another object of my invention is to provide 45 an acceleration pump in which the discharge of liquid fuel is controlled by gravity and may be made as gradual as desired regardless of the speed with which the pump is operated.

Still another object of my invention is to provide 50 an acceleration pump that is automatically self-scavenging as to fuel vapor formed therein by boiling of light fractions at the higher operating temperatures.

A still further object of my invention is to 55 provide an acceleration pump having an up-

turned fuel cup which is not evacuated of fuel by the vaporization of part of the fuel only, so that there is always some liquid accelerating charge available.

With these and other objects in view which 60 may be incident to my improvements, my invention consists in the combination and arrangement of elements hereinafter described and illustrated in the accompanying drawing in which:

Figure 1 is a side elevation of a carburetor 65 containing my improved acceleration pump, partly broken away to show the pump in vertical section.

Figure 2 is a fragmentary sectional view on a 70 larger scale of my improved pump at the beginning of its downward stroke.

Figure 3 is a similar view showing the piston at the end of its downward stroke.

Figure 4 is a similar view showing the piston 75 on its return upward stroke.

Figure 5 shows the position of the piston and pump upon the completion of its return stroke, and

Fig. 6 is a sectional view on the line 6—6 of Fig. 2.

Referring particularly to Figure 1, the reference numeral 1 denotes the body of a conventional carburetor which has the usual air intake 2, mixing chamber 3, and mixture outlet 4 controlled by a throttle valve 5. Fixed upon the 80 throttle shaft 6 is a cam 7 which bears upon and actuates a lever 8, pivoted at 9 and connected to a link 10 which in turn is connected to an inverted closed cylinder 11 by a ball and socket joint 24. Cylinder 11 forms a part of my improved acceleration pump and contains a loose-fitting hollow piston 12 which is mounted upon a fixed stud 13 and adapted to reciprocate thereon and within the cylinder 11.

Stud 13 is screwed into the bottom wall of 85 float chamber 14 and has an axial bore 15 which communicates through a passageway 16 with a main jet 17 projecting into the mixing chamber 3 of the carburetor. The upper part of stud 13 is in the form of an upturned cup 18 which 1 communicates through metering orifices 19 with the inside of hollow piston 12. The outside of cup 18 is hexagonal in shape so as to provide edges which form guides for piston 12 and intermediate spaces for the flow of liquid fuel from orifices 19 to cross passages 20 which communicate with axial bore 15 aforesaid.

The lower inner part of hollow piston 12 is 1 conical in shape so as to seat tightly on the conical shoulder 21 of cup 18 and close passages 20

when piston 12 is in its upper position. Piston 12 is held on its seat 21 by a spring 22 which engages the lower end of the piston and is seated on a stud 23 on the bottom wall of float chamber 14.

Regardless of how much vapor collects in cylinder 11, liquid fuel always remains in cup 18 and constitutes a reserve supply, so that the pump will never fail to deliver an accelerating charge when desired. Since the flow of liquid fuel from cup 18 through metering orifices 19 is controlled by gravity, it may be graduated as desired. The intake of the pump from the float chamber 14 is through the space between the cylinder 11 and piston 12.

The operation of my device is as follows. Whenever the throttle 5 is opened, cam 7, through lever 8 and link 10, depresses cylinder 11. But if the opening of the throttle 5 is gradual the liquid and vapor contents escape through the space between the cylinder walls and piston 12 and the piston 12 is not moved from its seat 21. Consequently there is no discharge from the pump into the mixing chamber 3 of the carburetor. If, however, the opening of the throttle 5 is sudden, there is not time enough for the escape of fluid through the space between the cylinder and piston. Accordingly a pressure is at once built up in cylinder 11 which unseats piston 12, opening passage 20 and forcing the liquid which drains from cup 18 through orifice 19 through bore 15, passageway 16 and main jet 17 into mixing chamber 3.

At low speeds and light loads the cylinder 11 remains in its upper position and the piston 12 is held to its seat 21 by the spring 22. As bubbles form in the liquid within cylinder 11 due to the boiling of the light fractions at higher operating temperatures and to the entrained air which is always present in pumped liquid fuel, they go to the top partially displacing the liquid in cylinder 11 as shown in Figure 2 so that the liquid level in cylinder 11 is below that in the float chamber 14. When the throttle 5 is suddenly opened the cylinder 11 is forced down as above described and the compression of vapor in the dome space of the cylinder forces the piston 12 down as far as it will go, compressing the spring 22 which is very light and of negligible force as regards varying the volume of the vapor in the cylinder, after which cylinder 11 may move downwardly a short distance further before its movement is arrested by contact with the upper edge of cup 18. The excess of the stroke of cylinder 11 over that of piston 12 permits a positive, rather than a yielding, compression of the contents of the cylinder, thereby producing an instantaneous discharge through jet 17, followed by a slower discharge as cylinder 12 is raised by spring 22. During the time that cylinder 12 is in its depressed position, Figure 3, the vapor will gradually pass down between the cylinder 11 and piston 12 and escape into the float chamber 14 which is suitably vented to the atmosphere. At the same time, whatever liquid is present in cylinder 11 and cup 18 will escape through passages 20 and some small amount between the piston 12 and stud 13.

After the throttle 5 has been held open a little while, spring 22 will begin to return piston 12 to its seat 21 and conditions will be as shown in Figure 4. During this phase, any liquid held in the bottom of piston 12 will be forced out through passages 20 by the pressure of vapor in cylinder 11 as the liquid level is raised by the

ascent of piston 12. Also during the ascending stroke of piston 12, the vapor in the dome of cylinder 11 will be forced out into float chamber 14 through the space between cylinder 11 and piston 12, and since passages 20 are kept liquid sealed by the liquid in piston 12, no vapor can escape through bore 15, passageway 16, jet 17 into mixing chamber 3. Also between conditions in Figures 3 and 4, the liquid in cup 18 has been gradually draining out so as to keep the liquid in cylinder 12 at or slightly above the level of the passages 20.

When the throttle is closed the cylinder 11 is raised and a fresh charge of fuel is drawn into the cylinder under considerable suction. Under these conditions, as shown in Figure 5, bubbles will promptly form again since the temperature of the fuel has not been changed, but the bubbles will collect in the top of cylinder 11 and conditions will assume the status illustrated in Figure 2 and the cycle above described will be repeated upon the next operation of the pump.

From the foregoing description, it is clear that I have devised a novel means of overcoming the present difficulties in the operation of acceleration pumps due to the formation and discharge of vapor.

While I have shown and described the preferred embodiment of my invention, I desire it to be understood that I do not confine myself to the constructional details disclosed as these may be readily changed and modified by those skilled in the art without departing from the spirit of my invention or exceeding the scope of the appended claims.

I claim:

1. In a carburetor, an acceleration pump comprising a cylinder in the form of a bell having an open mouth at its lower end, a piston reciprocating in said cylinder with a loose fit providing a channel for the escape of fuel vapor from said cylinder through said mouth, and an outlet for liquid fuel from said cylinder below the point of egress of fluid past said piston whereby no vapor is ejected into said liquid fuel outlet during the operation of the pump.

2. In a carburetor, an acceleration pump comprising a cylinder in the form of a bell having an open mouth at its lower end, a piston loosely fitting in said cylinder and providing a channel for the escape of vapor from said cylinder through said mouth, a liquid fuel outlet from said cylinder, and means for sealing said outlet with liquid fuel until said cylinder is completely emptied, whereby vapor is prevented from escaping through said outlet during the operation of the pump.

3. In a carburetor, an acceleration pump comprising a cylinder, a piston loosely fitting in said cylinder providing a channel for the escape of vapor from said cylinder, a liquid fuel outlet from said cylinder, means for preventing the escape of vapor through said outlet, and means for forcing said vapor through said channel whereby said cylinder is automatically scavenged of vapor during each operation of the pump.

4. In a carburetor, a liquid fuel accelerating pump comprising a hollow fixed stud terminating in a cup having hexagonal walls, a cylindrical piston reciprocating on said stud and engaging the edges of the hexagonal walls of said cup whereby channels are formed between the cup and piston for the circulation of liquid fuel therebetween.

5. In a carburetor, an acceleration pump comprising a cylinder, a cup within said cylinder for holding a reserve supply of liquid fuel, and a metering orifice in said cup whereby said liquid fuel is discharged at a regulated rate regardless of the vapor pressure in said cylinder. 80
6. In a carburetor, an acceleration pump comprising an upwardly extending outlet member, a fuel container having an aperture fitted over the outlet member and adapted to reciprocate thereon, and a fuel reservoir formed on the outlet member. 85
- 10 7. In a carburetor having a float chamber, an acceleration pump comprising an outlet member projecting into the float chamber, an open-ended inverted fuel container reciprocable on the outlet member, and a fuel reservoir associated with the outlet member and designed to furnish a flow of fuel for sealing the outlet port during operation of the pump. 90
- 15 8. In a carburetor, an acceleration pump comprising an outlet member terminating in a fuel reservoir and having an outlet port below the reservoir, a piston reciprocably mounted on the outlet member and designed to close said outlet port when in one position, and a fuel container reciprocably mounted on the piston. 95
- 20 9. In a carburetor, an acceleration pump comprising an outlet member terminating in a fuel reservoir having a restricted outlet, said outlet 100
- 25
- 30

member having an outlet port below the reservoir, a piston reciprocably mounted on the outlet member and designed to close said outlet port when the piston is in one position, and a manually controlled fuel container reciprocably mounted on the piston to force fuel through the outlet member.

10. In a carburetor, an acceleration pump comprising an outlet member, a cylinder reciprocable on the outlet member, and pressure relief means between the outlet member and cylinder operative to permit escape of vapor from the cylinder while retaining an acceleration charge of liquid fuel therein. 105

11. In a carburetor, a fuel reservoir, and an acceleration pump supplied from the fuel reservoir and comprising an outlet member, a cylinder reciprocable on the outlet member, and pressure relief means interposed between the outlet member and cylinder operative upon the development of a predetermined pressure within the cylinder to permit escape of vapor from the cylinder to the fuel reservoir while retaining an acceleration charge of liquid fuel therein. 110

12. A device as defined in claim 11, wherein the pressure relief means comprises a yielding piston slidable relative to the outlet member and cylinder and operative to close the outlet member. 115
